UNITED STATES PATENT OFFICE.

CHARLES SMITH, OF CHICAGO, ILLINOIS, ASSIGNOR TO CHARLES SMITH COMPANY, OF CHICAGO, ILLINOIS, A CORPORATION OF ILLINOIS.

DESIGN FOR A HEATING-FURNACE FRONT.

No. 37,927.

Specification for Design.

Patented March 27, 1906.

Application filed February 7, 1906. Serial No. 300,011. Term of patent 14 years.

To all whom it may concern:

Be it known that I, CHARLES SMITH, a citizen of the United States, residing at Chicago, in the county of Cook and State of Illinois, have invented a new, original, and ornamental Design for Heating-Furnace Fronts, of which the following is a specification, reference being had to the accompanying drawing, forming a part thereof.

The figure is a front view of a heating-furnace front, showing my new design.

I claim—

The ornamental design for a heating-furnace front, as shown.

CHARLES SMITH.
